UNITED STATES PATENT OFFICE.

ROBERT W. WOLFF, OF SOUTH ERLANGER, KENTUCKY.

PLATEN FOR TYPE-WRITING MACHINES.

964,599.

Specification of Letters Patent.

Patented July 19, 1910.

Application filed October 2, 1909. Serial No. 520,646.

To all whom it may concern:

Be it known that I, ROBERT W. WOLFF, a citizen of the United States, residing at South Erlanger, in the county of Kenton and State of Kentucky, have invented certain new and useful Improvements in Platens for Type-Writing Machines, of which the following is a specification.

My invention relates to platens for type-writing machines, and has for its object the provision of a platen or cylinder of the character mentioned so constructed and arranged that the noise incident to the striking impact of the type may be reduced or avoided, and the invention consists in the parts and in the construction, arrangement and combination of parts hereinafter described and claimed.

In the drawings: Figure 1 is a side elevation of my improved device, partly broken away, and partly in longitudinal axial section. Fig. 2 is a cross-section of the same on the line $z-z$ of Fig. 1. Fig. 3 is a cross-section of the same on the line $y-y$ of Fig. 25 1. Fig. 4 is an outside end elevation of one of the end-supporting members. Fig. 5 is an axial section of the same. Fig. 6 is an inside end elevation of one of the bearing-pieces; and, Fig. 8 is an inside end elevation of the other bearing-piece.

A represents a shell which is preferably of hard substance, being preferably made of metal, for instance steel tubing or aluminum, 35 and imperforate.

B B are end-supporting members, the inner ends of which support the shell and the outer ends of which are supported on the outer bearing-pieces C D, the inner ends 40 of the end-supporting members preferably having centering parts thereon for centering the shell with relation thereto, and the outer ends of the end-supporting members having centering parts thereon for being centered 45 on the bearing-pieces. The end-supporting members are shown in the form of half-spoons and are preferably made of wood or other fibrous material.

The support between the shell and the end-supporting members is preferably provided by forming the end-supporting members with central bosses b b snugly received in the bore of the shell. The support between the bearing-pieces and the end-supporting members is preferably formed by forming said bearing-pieces in the form of

disks provided with inwardly extending bosses c d which are snugly received in annular recesses b' b' in the outer faces of the end-supporting members. The inner ends 60 of the bosses c d are preferably spaced from the bottoms of the recesses b' b' by the spaces b² b². The bearing-disks are secured to the end-supporting members by means of screws E passing through apertures c' d' 65 in the disks and screwed into the end-supporting members, the screws preferably extending parallel to the axis of the platen. One of the bearing-disks may have suitable ratchet-teeth d² thereon for being engaged 70 by the usual pawl of the typewriting machine.

The bearing-pieces have bearings c² d³ thereon which snugly receive a shaft F, the shaft passing through central axial apertures b³ b³ in the end-supporting members, these axial apertures being preferably of greater diameter than the diameter of the shaft, and a shell A being hollow, so that the sole support of the platen upon the shaft 80 may be received by the bearing-pieces C D.

G is an outer covering, preferably of resilient material such as rubber, which preferably has an inner lining H of fabric. This covering is preferably of cylindrical 85 form and is received over the annular flanges b⁴ b⁴ of the end-supporting members at the respective ends thereof so as to leave an annular space I between the shell and said covering. Pins g may be driven through the 90 outer covering and lining into the annular flanges for aiding in holding the same against relative displacement. A sound-deadening substance is received in said annular space 95 and is indicated at K. This substance may be any substance suitable for the purpose. It may for instance consist of a composition of one part gelatin, two parts glycerin, and one-fourth part glucose. The sound-deadening substance, composition or filling 100 is preferably inserted by pouring the same into said annular space between the shell and outer covering while in plastic state, preferably while but one of the end-supporting members is in place, the other end-supporting member being inserted in place after the filling of said space, the setting of said substance securely binding the parts together, the fabric lining H, shown as a single layer of textile fabric, being interposed between the filling and the outer covering, and forming a binding member

between the outer covering and the filling. The filling when set is preferably resilient and forms a substantially noiseless backing for the outer covering so as to receive the impact of the blows of the type with substantially no or but slight attendant noise. The shaft may be journaled in suitable bearings L of a typewriting machine and be provided with turning-knobs M, and the platen 10 secured to the shaft by a set-screw f.

My improved construction is such that the parts are readily assembled and it forms a platen in which the noise incident to the impact of the type is minimized. The outer covering is preferably received about the periphery of the annular flanges of the end-supporting members, the shell and end-supporting members having portions which extend into each other's radial planes for centrally disposing and supporting the shell upon the end-supporting members, and the bearing-pieces and end-supporting members have parts thereon which extend into each other's radial planes for supporting the end-supporting members centrally with relation to the bearing-pieces, so that all the parts are arranged and supported centrally with relation to the supporting shaft which passes unobstructedly longitudinally through the middle of the parts mentioned so that the cylinder may be placed upon the shafts of various makes of typewriters and substituted for the cylinders which may be therein. The construction further permits the platen 35 to be turned by a turning-knob at the end of the shaft, making the parts self-contained and readily insertible and removable from the typewriting machine. My improved construction further permits bearing-pieces 40 of various kinds to be secured to the end-supporting members so as to support the platen in various kinds of typewriting machines. It will be further noted that these bearing-pieces and the shaft are removable 45 without affecting the integrity of the platen.

Having thus fully described my invention, what I claim as new and desire to secure by Letters Patent is:

1. In a platen for typewriting machines, the combination of end-supporting members, a shell centrally supported between said end-supporting members, an outer covering, a sound-deadening filling between said shell and covering, and bearing-pieces removably secured to said end-supporting members.

2. In a platen for typewriting machines, the combination of end-supporting members, a shell supported between said end-supporting members, an outer covering, a sound-deadening filling between said shell and outer covering, a shaft, and bearing-pieces removably secured to said end-supporting members and having bearings thereon snugly fitting said shaft, said end-supporting members and shell having bores of greater diam-

eters than the diameter of said shaft, for the purpose described.

3. In a platen for typewriting machines, the combination of a shell, an end-supporting member for the end of said shell, and a bearing-piece for said end-supporting member, said bearing-piece and end-supporting member having a recess and boss between them located in each other's radial planes for centrally supporting said end-supporting member from said bearing-piece, and said end-supporting member and shell having a recess and boss between them located in each other's radial planes for centrally supporting said shell from said end-supporting member, an outer covering received about said shell, there being an annular space between said outer covering and said shell, and a sound-deadening substance in said space, substantially as described.

4. In a platen for typewriting machines, the combination of an inner shell, end-supporting members at the respective ends of said shell, bearing-pieces having bosses for said end-supporting members, said end-supporting members having inwardly extending bosses at their inner faces and inwardly extending recesses at their outer faces, the respective ends of said shell received about said inwardly extending bosses on said end-supporting members and said recesses receiving said bosses on said bearing-pieces, an outer covering received about said shell, there being an annular space between said outer covering and shell, and a sound-deadening substance received in said space, substantially as described.

5. In a platen for typewriting machines, the combination of an inner shell, end-supporting members at the respective ends of said shell, bearing-pieces having bosses for said end-supporting members, said end-supporting members having inwardly extending bosses at their inner faces and inwardly extending recesses at their outer faces for forming undercut radial flanges, the respective ends of said shell received about said inwardly extending bosses on said end-supporting members and said recesses receiving said bosses on said bearing-pieces, the said recesses being deeper than the length of said last-named bosses, an outer covering received about said flanges, there being a space between said flanges and said outer covering and shell, and a sound-deadening substance received in said space, for the purpose described.

In testimony whereof, I have signed my name hereto in the presence of two subscribing witnesses.

ROBERT W. WOLFF.
